UNITED STATES PATENT OFFICE.

JOHN P. LUXMORE, OF CHICAGO, ILLINOIS.

DESIGN FOR A CLOCK-CASE, &c.

SPECIFICATION forming part of Design No. 25,022, dated December 31, 1895.

Application filed September 7, 1895. Serial No. 561,865. Term of patent 7 years.

To all whom it may concern:

Be it known that I, JOHN P. LUXMORE, a citizen of the United States, residing at Chicago, in the county of Cook and State of Illinois, have invented a certain Design for Office-Reminders, of which the following is a specification.

My invention relates to a design for a case for clocks, reminders, &c.

The design is illustrated in the accompanying drawings, wherein—

Figure 1 is a side elevation, and Fig. 2 is a perspective.

Like parts are indicated by the same letters in both the figures.

A is a substantially circular base-molding surmounted by the curved pedestal B, on

which rests the substantially semiglobular part C, which is cut away below, as it were, to rest upon the top of the part B, and has the inclined surface plate D. The general effect is that of a globe or hemisphere with its flat surface inclined so as to be readily looked upon by the person sitting in proximity to the design, and with its lower portion resting upon a curved or molded base, as described.

I claim—

The design for a clock or reminder case, substantially as shown and described.

JOHN P. LUXMORE.
